TOY FORK LIFT

Ernest Casper Wolf, 919 Washington SE,
Albuquerque, N. Mex. 87108

Filed Mar. 17, 1972, Ser. No. 235,886

Term of patent 14 years

Int. Cl. D21—01

U.S. Cl. D34—15 T

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 1 is a perspective view of the fork lift design in accordance with the invention, illustrating the front, left side, and top of the fork lift, with the movable fork lift member in a lowered position.

FIG. 2 is a right elevational view of the fork lift design of FIG. 1 illustrating the movable fork lift member in a raised position.

FIG. 3 is a rear elevational view of the fork lift design of FIG. 1, with the movable fork lift member in a lowered position.

FIG. 4 is a front elevational view of the fork lift design of FIG. 1, with the movable fork lift member in a lowered position.

FIG. 5 is a top plan view of the fork lift design of FIG. 1, with the movable fork lift member in a lowered position.

FIG. 6 is a right elevational view of the fork lift design of FIG. 1, with the movable fork lift member in a lowered position.

FIG. 7 is a bottom view of the fork lift design of FIG. 1.

FIG. 8 is a perspective view of an alternative embodiment of the fork lift design, in accordance with the invention, showing the front, left side, and top of the alternative design of the fork lift, with the movable fork lift member in a lowered position.

FIG. 9 is a right elevational view of the fork lift design

of FIG. 8, with the movable fork lift member in a raised position.

FIG. 10 is a rear elevational view of the fork lift design of FIG. 8 with the movable fork lift member in a lowered position.

FIG. 11 is a front elevational view of the fork lift design of FIG. 8, with the movable fork lift member in a lowered position.

FIG. 12 is a top plan view of the fork lift design of FIG. 8, with the movable fork lift member in a lowered position.

FIG. 13 is a right elevational view of the fork lift design of FIG. 8, with the movable fork lift member in a lowered position.

And FIG. 14 is a bottom plan view of the fork lift design of FIG. 8, with the movable fork lift member in a lowered position.

I claim:

The ornamental design for a toy fork lift, as shown and described.
